UNITED STATES PATENT OFFICE.

CAMILLE JORIOT, OF LAC-ON-VILLERS, FRANCE.

PISTOL AND MECHANISM WHICH CAN BE CONCEALED IN ANY PORTABLE OBJECT.

Application filed November 6, 1922. Serial No. 599,389.

To all whom it may concern:

Be it known that I, CAMILLE JORIOT, a citizen of the French Republic, residing at Lac-on-Villers, in the Department du Doubs and Republic of France, have invented certain new and useful Improvements in Pistols and Mechanisms Which Can be Concealed in Any Portable Object, of which the following is a specification.

10 The present invention relates to a pistol which can be concealed, with its mechanism, in any portable object such as for example: a walking stick, sunshade, umbrella, whip, hunting crop, sundry weapons, policeman's 15 truncheon and the like. It can also be applied to any object not having a handle and which can be grasped at the part containing the device forming the object of the invention such for example as a feather-brush, 20 broom, butcher's saw, marine telescope or the like.

The device may also be concealed in any fixed or movable object, such as an iron or wooden door-bar, brake-lever or change-speed lever of motor-cars, perambulators, hand-cars, travelling-bag handles, bicycle handle-bar, or the like, in short in any part of an article of furniture, a tool or even in any place forming part of a dwelling.

25 To enable the invention to be more readily understood, it is described hereinafter as applied to a walking stick, which is shown in general view in the annexed drawings, where:

30 Fig. 1 is the handle of a walking stick, provided with a recess for the mechanism.

Fig. 2 is a sectional view of the butt, with the pistol.

Fig. 3 is an end view of the pistol.

35 Fig. 4 is an end view of the butt.

Fig. 5 is a section on the line $a-a$ of Fig. 2.

Fig. 6 is a view analogous to that of Fig. 2, the pistol itself being removed.

40 Fig. 7 shows the butt, detached from the remainder of the walking stick.

Fig. 8 represents the mechanism intended to be lodged in the handle of the walking stick.

45 Fig. 9 represents the mechanism in another position.

Fig. 10 shows the mechanism with the striking pins "cocked."

Fig. 11 shows the mechanism with the striking pins uncocked. 55

Fig. 12 is a view of the base plate of the mechanism.

Fig. 13 is another view of this plate.

Fig. 14 shows the said plate in another position. 60

Fig. 15 is an end view as seen from the front end of the mechanism.

Fig. 16 shows the plate in another position. 65

Fig. 17 is an end view as seen from the rear end of the mechanism.

Fig. 18 shows the pin intended to cock the piston in the butt and the striking pins of the mechanism.

Fig. 19 represents a detail. 70

Fig. 20 represents the invention in general view as applied to a bag of textile fabric.

Fig. 21 is a cross section of the upper part of the bag.

Fig. 22 represents the arrangement as applied to a leather bag. 75

Fig. 23 shows a bag to which the pistol is fixed in three points.

Fig. 24 is a view of the revolving plate of the mechanism. 80

The walking stick to which the object of the present invention is applied consists of 4 parts; the handle 1 containing the mechanism described hereinafter; the cylinder or pistol 2 containing the barrels; the butt 3 85 making part of the walking stick and the end 4, which is an extension of the butt.

The handle 1 which may have any desired form, as illustrated, is provided near the curved part with a hollow 5 intended to 90 receive the mechanism. The end of this handle is threaded at 6 so as to enable it to engage with the screwed part 7 of the cylinder or pistol 2.

The cylinder 2 comprises two barrels 8, at the entrance of which the cartridges are inserted; in this cylinder there is likewise, under the barrels 8, a longitudinal hole 9 through which a pin 17 may be passed. The butt comprises a tube 3 in which a piston 11 can move, said piston having two pins 12 which engage in the barrels 8 of the pistol 2. The piston 11 is connected to a strong spiral spring 13, which is fixed at its other end to the bottom of the tube at 100 14. This piston 11 has at its front end a

105

threaded hole 15 into which the end of the pin 10 may be screwed; it is also provided with a spring stop 16 and a stem 17. The end 20 of the stem 17 carries a stop arrangement comprising a form of lever, with a pivoting point in the centre at 20', and of which the end 20" (Fig. 8) is displaced from the centre line so that in bearing upon the bottom of the hole 30 (Fig. 11) the device engages the plate 18 of the mechanism disposed in the handle. The tube 3 is provided with an inside recess 17' formed as an inclined plane over one half of the circumference of the said tube. To displace the piston 11 ready to receive the pistol 2 as shown in Figure 2 the pin 10 is screwed into the threaded hole 15 and the pin 10 is pulled until the stop 16 drops into the recess 17'; the piston then occupies the position shown in Fig. 6; in this position the pins 12 project and can engage in the barrels 8.

The end 4 of the walking stick is connected with the butt by a pin or any other suitable means.

25 The mechanism intended to be lodged in the recess 5 of the handle 1 of the walking stick comprises a metallic block having a revoluble plate 18 provided with holes the unperforated part engaging with the striking pins when cocked.

30 The rear of this plate 18 which is actuated by a lever 19 operating as a sear engages the stop 20 of the pin 17 of the piston 11 (Fig. 8). The plate 18 has teeth 21 which in succession are engaged by a pawl or click 22, formed integral with the lever 19.

35 The mechanism moreover comprises a "finger" 23, an inclined plane 24 and several springs. The block is introduced into the recess 5 of the handle where it is kept in place by a groove with which a finger 26 engages. A nut is screwed into the recess 5 intended for the mechanism so as to keep the 40 said mechanism in place. This nut is of steel and is pierced with holes intended to allow the striking pins to pass therethrough; moreover it intercepts foreign matter which might get into the mechanism and prevent 45 its action. To "cock" the striking pins the pin 10 is screwed into the hole 27 said pin being pulled back to the end of its travel; in this movement, the ends 28 of the striking pins are disposed behind the plate 18; the 50 finger 23 engaging in the inclined plane 24, thus displacing the pawl or click 22, whereupon the plate 18 returns to its initial position under the action of the spring 29. Uncocking is effected by pressing on the 55 sear 19.

55 The walking stick being mounted, the following procedure is adopted in order to load and discharge it.

60 (1). Introduce the pin 10 through the hole 31 of the handle 1 and screw it into the

threaded hole 27; then pull back, to the end of its travel. The purpose of this movement is to "cock" the striking pins and when this is effected the pin is unscrewed and withdrawn from the hole 31.

65 (2). Unscrew the handle at 6, introduce the cartridges into the barrels and screw on the handle again. The pistol is now loaded.

(3). Hold the butt 3 with the left hand, screw the pin 10 into the hole 15, and "cock" 70 the piston 11 in the manner as stated above, by pulling it until the stop or catch 16 engages with the groove 17', then withdraw the pin 10.

(4). Introduce the stem 17 into the hole 9 and the pins 12 into the barrels; push well home, and turn the butt in the left hand to the right until disengagement takes place owing to the stop 16 cooperating with the inclined plane in the groove 17. As soon 80 as this disengagement has taken place, all the parts are associated with each other and with the spring 13, and the walking stick then presents the appearance of an ordinary 85 walking stick. It is ready to be used as a 90 fire-arm.

95 In order to shoot, press the lever 19 down to the end of its travel, when the plate 18 will rotate to the extent of the first tooth and expose an orifice which affords a passage to the stop 20 of the pin 17. The spring 13 brings the piston 11 back into the 100 butt and the pins 12 issue from the barrels. The butt is then separated from the walking stick and the piston and the springs occupy in the butt the position shown in Fig. 7. Therefore, there remains in the hand of the person who is using the walking stick, the handle to which the pistol is always screwed. During this first movement of the plate 18 the striking pins remain "cocked," their ends resting against the unperforated part of the said plate. On allowing the sear 19 to rise again under the action of its spring, the click or pawl 110 22 catches into the second tooth of plate 18 and if the sear 19 is operated a second time the plate 18 rotates to the extent of the length of travel of the second tooth and brings one of the orifices opposite to the first striking pin, which by traversing this orifice discharges the first shot. On operating the sear lever 19 a third time, the second shot is fired.

115 With this walking stick, accidents are 120 impossible, supposing that it were to fall and that the disengagement of the stop 20 were effected, it would still be necessary to press on the sear in order to let the striking pins go. However a safety arrangement 125 has been provided. It consists of a pin 32 (Fig. 10) which may bear at one of its ends the letter F (fire) and at the other end the letter S (safety). This pin which 130 can be operated from outside, acts on a lever

33 which can engage the sear lever 19, and may be hidden by a moveable ferrule forming an ornament on the walking stick handle.

5 In the arrangement as shown, the sear lever does not project from the walking stick and is not visible as it is covered by a superimposed piece which blends with the surrounding parts of the stick and is 10 painted the same colour as the latter. In order to operate the sear it is only necessary to press upon the superimposed piece. Obviously, this piece might be replaced by a projecting knob without thereby modifying the principle of the invention.

The walking stick may be arranged for more than 2 shots. If for instance it were arranged for 3 shots, it would be necessary to have 3 barrels, and three striking pins, 20 and one tooth would have to be added on the plate.

If it were desired to transform an existing fire-arm for example a "Browning," this transformation would necessitate the 25 use of one of the parts of the mechanism forming the subject of the present invention.

It is obvious that one might combine with this pistol a known extractor device, 30 which would permit ejecting the fired cartridge-cases automatically.

The tubes, envelopes and the like are of light and unoxidizable metal, for instance, of "duralumin."

35 Similarly, the piston, the pins, the mechanism as well as all the parts brought into direct contact with steel, or, as far as possible, one of these parts is made of "duralumin" in order that no rust may be formed.

40 In most fire-arms, the "cocked" striking pins are directly opposite the cartridges. The mechanism of the pistol forming the subject of the present invention presents the peculiarity that the cartridges are separated from the striking pins by a revolvable plate. This novel arrangement therefore permits of a maximum of security being obtained. It will also be noted that the first action exercised on the sear lever separates the walking stick or other article into two parts, and by continuing to press on the same lever the cartridges are fired.

45 It goes without saying that the pistol may be advantageously utilized without disguising it, as it forms an excellent weapon of defence, owing to the rapidity with which it can be brought into action, as well as the absolute security it affords when in a state of rest.

50 By way of variation, the present invention is shown as applied to a bag of textile fabric (Fig. 20). This bag is mounted on three bars 32', 33' and 34. The pistol and its mechanism are concealed in 35, which is 55 connected with 34, but can be detached

therefrom by pressing on the catch lever, as in the case of the walking stick described above; 34 and 35 are arranged above 33' to which they are connected by a coupling 36. 70 37 forms a second coupling. 32' comprises a clamp which connects it with 33'; on disengaging this clasp 32' and 33' may be separated to open the bag which is fixed to buckles or rings which slide on the staves.

75 For a leather bag or valise the handle of a walking stick is placed in the centre thereof, the part 38 (Fig. 22) of said handle being introduced into the said bag so that on pressing on the sear lever, as has been stated above, there remains nothing in the hand but the handle with the pistol. In some cases a carrying cover might also be combined with this arrangement.

80 If the leather bag in question is to carry rather a heavy load the following arrangement may be adopted said arrangement permitting fixing to the bag, in three points, the part containing the pistol and its mechanism. In this case there is no curved handle. The pistol is fitted with a revolving plate 39, provided with a notch 41 and a rim 42 (Figs. 23 and 24) but the butt, the piston and associated mechanism are replaced by a spring click 40 which engages on to the plate 39; in turning this plate the notch 41 (Fig. 24) arranged in the rim 42 arrives opposite the click or pawl 40 and at this moment the click 40 passes through this notch under the weight of the load. The click or pawl 40 is lodged in a mounting 43

90 in the form of a reversed letter T of which the ends 44, 45 bear articulated clicks (or pawls) 46, 47 provided with springs at the sides. The load carried by the click 40 compresses the clicks 46 and 47 and clamps them into the extremities 48, 49 of the pistol. The latter is therefore well connected with the bag in three points. To support the load until the clicks (or pawls) 46, 47 are hooked on to the extremities of the pistol the click 40 is provided in its longitudinal direction with a strong spring 50. The clicks (or pawls) 46, 47 are hidden in an envelope or otherwise so that nothing in the appearance of the bag will reveal the presence of a fire-arm. By pressing on the catch levers the clicks or pawls 46, 47 are separated from the bag so that only the pistol remains in the hand. It will be seen that when the pistol is fixed in several points, as in the bag described above, it may be detached by a single movement, that is by pressing on the catch-lever.

100 110 115 120 125 It is well understood, that this pistol and its parts are capable of modifications which if they answer the purpose indicated in this specification will come within the scope of the present invention.

What I claim is:

130 A pistol mechanism, adapted to be con-

cealed in a portable object, comprising the combination with a plurality of striking or firing pins, of a revoluble plate having at its edge a series of teeth, said plate being provided with a plurality of holes for the passage of said pins when said holes are brought into register with said pins, said plate normally serving to hold said pins in "cocked" position, and means for rotating said plate step by step to permit the pas-

sage of said pins through said plate in successively firing the cartridges placed in barrels in the pistol.

In testimony whereof I affix my signature, in presence of two witnesses.

CAMILLE JORIOT.

Witnesses:

CHARLES DILIR,
LUCIEN CRESSING.
